ABSTRACT

A building element for use as a room wall provided with a door frame in which the top component or lintel is formed with first and second openings for connection with first and second air shafts, with the second opening being adapted to communicate with ventilating openings leading to the room and the vertical components or jambs having passages leading to the first opening and ventilating openings, respectively.

ROOM WALL BUILDING ELEMENT INCLUDING A DOOR-FRAME

BACKGROUND OF THE INVENTION

This invention relates to a building element for use as a wall for a room or other enclosure and which includes a door-frame.

The invention has as its object to provide a building element, which a door-frame includes air ducts capable of being easily connected to shafts or conduits for fresh air and used air so that the fresh air can be fed or introduced into the room at the ceiling and the used air removed at the floor level, or vice versa.

SUMMARY OF THE INVENTION

A building element for use as a wall for a room and including a door-frame having a top component and upright components, said frame being mounted in an opening in a wall, the top component of the door-frame being provided with a first opening connected to a first air shaft, and with a second opening connected firstly to a second air shaft and secondly to an air valve opening to the room side of the wall in proximity to the ceiling of the room, and the upright components of the door-frame being provided with passageways extending axially thereof, with their upper ends connected to said first opening and their lower ends to air valves opening to the room side in proximity to the floor. The upright components may, in addition, include passageways for electric lines, and recesses for switches and sockets, if desired, can be arranged at the desired heights on the upright components. The building element preferably is manufactured of steel sheet metal, possibly with certain details made of plastic. The element is preferably of symmetrical design and is provided with suitable means for its securing in the ceiling, floor and walls. The door-frame is provided with holders for hinges and with a box having a cover for the locking elements of the door.

BRIEF DESCRIPTION OF THE DRAWINGS

The invention is described in greater detail in the following, with reference to the accompanying drawings.

FIG. 1 is a diagrammatic view in elevation of a ceiling high building-element according to the invention.

FIG. 2 is a view in a vertical section through an upright component for the door-frame in the building element of FIG. 1.

FIGS. 3-6 are views on an enlarged scale taken along lines 3-3, 4-4, 5-5 and 6-6 and respectively of FIG. 1.

DETAILED DESCRIPTION OF THE INVENTION

The building element shown comprises two uprights components or jambs 1, one top component or lintel 2 and a bottom component or sill 3. The element is mounted in an opening in a wall 11 constituting a separation or partition wall between a room 13 and a hall or corridor 14. The element is provided with flaps or ears 10 by which the element is secured in the wall 11 as illustrated in FIG. 4. The flaps 10 are hidden by a board 12 mounted in a customary manner.

The top component 2 is designed as a box, which by a horizontal wall 15 is divided into upper and lower spaces 4, 6. The space 4 forms a second opening con-

stituting a ventilating opening leading to the room side, with such opening, for example, being provided with an air valve 8. The opening leading to the hall side is connected to a second air shaft 5.

5 The space 6 which constitutes a first opening communicates with longitudinal passageways 9 in the upright components 1 and is connected to the hall side with a first air shaft 7. For concealing the air shafts 5, 7, the hall preferably is provided with a sub-ceiling on the like 16. The passageways 9 are downwardly connected to ventilating openings leading to the room, for example in the form of air valves 17.

The upright components 1 further include ducts 18 for electric lines, and such ducts preferably are designed to form stops for a door 21, as illustrated in FIG. 4. The upright components are provided at desired heights with openings 19, 20 and boxes 27 located behind the openings are for the mounting of switches 22 and sockets. When one of the openings is not utilized, it can be covered by a lid or equivalent closure. The boxes 27 communicate with the ducts 18, thus allowing for the drawing of lines to the switches and sockets.

25 The air shaft 5 can be used for the supply of fresh air, preferably via a hot-air unit, and the shaft 7 for the evacuation of air, or vice versa. The room air preferably is partially returned to the hot-air unit. Some part of the room air is conveyed to the hall and evacuated therefrom through the kitchen, bath-room, corresponds and like spaces which are equipped with ventilation means. The latter part of the room air is removed from the room through openings 23 in a floor fillet or molding 24, which either is designed to provide a passageway per se or covers a passageway 25 located in the wall. The passageway 25 communicates with the hall through openings 26, or the passageway 25 may communicate with the lower portion of the upright components 1 with the lower portion of the upright component 1 in such a case being provided with an air opening to the hall which, thus, corresponds to the opening 26 shown in the drawing.

I claim:

45 1. A building element for use as a wall for a room and including a door-frame having a top component and upright components, said frame being mounted in an opening in a wall, the top component of the door-frame being provided with a first opening connected to a first air shaft, and with a second opening connected firstly to a second air shaft and secondly to an air valve opening to the room side of the wall in proximity to the ceiling of the room, and the upright components of the door-frame being provided with passageways extending axially thereof with their upper ends connected to said first opening and at their lower ends to air valve openings leading to the room in proximity to the floor.

2. A building element according to claim 1, characterized in that the upright components are provided with further ducts for receiving electric lines.

3. A building element according to claim 2, characterized in that the upright components are provided with recesses for receiving switches and sockets for use with the electric lines.

65 4. A building element according to claim 1, characterized in that said top component is a box and a horizontal wall divides the interior of the box into

UNITED STATES PATENT OFFICE
CERTIFICATE OF CORRECTION

Patent No. 3,637,052

Dated August 29, 1972

Inventor(s) Erik Schonberg

It is certified that error appears in the above-identified patent
and that said Letters Patent are hereby corrected as shown below:
